(57) **CLAIM**

The ornamental design for a diamond-shaped candy, as shown and described.

DESCRIPTION

The intended use of the article in which the design is embodied is for edible candies such as chocolate candies.

FIG. 1 is a top view of a first embodiment of a diamond-shaped candy, showing my new design;

FIG. 2 is a bottom view thereof;

FIG. 3 is a side view thereof, the opposite side being identical;

FIG. 4 is perspective view thereof from the top and one side;

FIG. 5 is a top view of a second embodiment of a diamond-shaped candy;

FIG. 6 is a bottom view thereof;

FIG. 7 is a side view thereof, the opposite side being identical;

FIG. 8 is a side view thereof, the opposite side being identical;

FIG. 9 is perspective view thereof from the top and one side;

FIG. 10 is a top view of a third embodiment of a diamond-shaped candy;

FIG. 11 is a bottom view thereof;

FIG. 12 is a side view thereof, the opposite side being identical;

FIG. 13 is a side view thereof, the opposite side being identical;
FIG. 14 is a side view thereof;
FIG. 15 is perspective view thereof from the top and one side;
FIG. 16 is a top view of a fourth embodiment of a diamond-shaped candy;
FIG. 17 is a bottom view thereof;
FIG. 18 is a side view thereof, the opposite side being identical;
FIG. 19 is a side view thereof, the opposite side being identical;
FIG. 20 is perspective view thereof from the top and one side;
FIG. 21 is a top view of a fifth embodiment of a diamond-shaped candy;
FIG. 22 is a bottom view thereof;
FIG. 23 is a side view thereof, the opposite side being identical;
FIG. 24 is a side view thereof, the opposite side being identical;
FIG. 25 is a side view thereof;
FIG. 26 is perspective view thereof from the top and one side;
FIG. 27 is a top view of a sixth embodiment of a diamond-shaped candy;
FIG. 28 is a bottom view thereof;

FIG. 29 is a side view thereof, the opposite side being identical;
FIG. 30 is a side view thereof, the opposite side being identical;
FIG. 31 is a side view thereof;
FIG. 32 is perspective view thereof from the top and one side;
FIG. 33 is a top view of a seventh embodiment of a diamond-shaped candy;
FIG. 34 is a bottom view thereof;
FIG. 35 is a side view thereof, the opposite side being identical;
FIG. 36 is a side view thereof, the opposite side being identical;
FIG. 37 is perspective view thereof from the top and one side;
FIG. 38 is a top view of an eighth embodiment of a diamond-shaped candy;
FIG. 39 is a bottom view thereof;
FIG. 40 is a side view thereof, the opposite side being identical;
FIG. 41 is a side view thereof, the opposite side being identical; and,
FIG. 42 is perspective view thereof from the top and one side.
